UNITED STATES PATENT OFFICE.

JOHN CHRISTIE, OF IRVINE, PENNSYLVANIA.

DRAFT-RIGGING FOR CAR-COUPINGS.

SPECIFICATION forming part of Letters Patent No. 609,410, dated August 23, 1898.

Application filed February 23, 1898. Serial No. 671,297. (No model.)

To all whom it may concern:

Be it known that I, JOHN CHRISTIE, a citizen of the United States, residing at Irvine, in the county of Warren and State of Pennsylvania, have invented a new and useful Draft-Rigging for Car-Couplings, of which the following is a specification.

The invention relates to improvements in draft-rigging for railway-cars having vertical plane car-couplings of the Janney type, and has for its object to provide a simple, inexpensive, and efficient device adapted, should a draw-head become disconnected from the draft mechanism, to prevent the said draw-head from being pulled entirely out from its car and falling upon the track.

The invention consists in the construction and novel combination and arrangement of parts hereinafter fully described, illustrated in the accompanying drawings, and pointed out in the claims hereto appended.

In the drawings, Figure 1 is a perspective view showing a car-coupling mounted on a car in accordance with this invention. Fig. 2 is a longitudinal sectional view of the same. Fig. 3 is a transverse sectional view on line 3 3 of Fig. 2. Fig. 4 is a similar view on line 4 4 of Fig. 2. Fig. 5 is a detail view of the supporting frame or stirrup. Fig. 6 is a similar view of the safety-key. Fig. 7 is a detail view of the locking-washer.

Like numerals of reference designate corresponding parts in all the figures of the drawings.

1 designates a vertical-plane draw-head provided with a pivoted knuckle and adapted to couple with a corresponding draw-head in the usual manner. The shank 2 of the draw-head is supported within a rectangular frame or stirrup 3, conforming to the configuration of the shank or draw-bar and arranged between the longitudinal draft-timbers 4 of a car 5 and provided at the lower edges of the said draft-timbers with laterally-extending flanges 6, perforated for the reception of bolts 7, which pass through the flanges, the draft-timbers, and the end sill 8 and secure the frame or stirrup to the car.

The rectangular frame or stirrup, which supports the draw-head and operates as a carrier-iron, is composed of a horizontal bot-

tom plate, of which the said flanges 6 are extensions, vertical sides, which are arranged at the inner faces of the draft-timbers 4, and a top plate, the top and sides of the frame or stirrup serving as chafing-irons and protecting the timbers of the car from wear. The top of the frame or stirrup is provided at its rear edge with a vertical flange 3^a, arranged in a recess of the rear face of the end sill 8 and engaging the same. By means of the flange 3^a and the bolts 7 the frame or stirrup is firmly fixed to the car. The rectangular frame or stirrup also serves as a stop and is adapted to be engaged by a safety-key 9, extending vertically through slots 10 of the shank of the draw-head and adapted to engage the top and bottom of the frame or stirrup should the draw-head become disconnected from the draft mechanism, whereby the said draw-head will be prevented from being drawn out from the car and from falling upon the track.

The longitudinal bore or opening of the shank of the draw-head is cylindrical and of the same diameter, and the safety-key 9, which is adapted to engage the stop, consists of a spherical body portion or ball 11 and oppositely-disposed arms 12, the ball fitting snugly within the longitudinal bore or opening and the arms projecting through the slots 10. The key is adapted to be readily introduced into and removed from the draw-head after the latter is mounted on the car, and said key is inserted endwise, and after being brought opposite the slots 10 it is partially rotated to cause the arms to project through the slots. The arms are provided with perforations, and the lower one receives a ring 13 or other suitable device to retain the safety-key in a vertical position and prevent the arms from leaving a position for engaging the frame or stirrup.

The rear end of the shank of the draw-head is connected by a tail pin or bolt 14 with a follower-plate 15 of the ordinary construction. The head of the bolt or pin is mounted within the shank of the draw-head, and the rear or the inner end of the same is slotted to receive a vertical key 16, which is provided at its upper end with a head, and is perforated below the bolt or pin 14 to receive a fastening

- device to prevent it from being accidentally withdrawn. The key 16 fits in a groove 17 of a locking-washer 18, which is interposed between the key and the follower-plate and which fits snugly between the sides of the draft-timbers. The front edge of the key is rounded and the groove of the locking-washer is concave in order to keep the edge of the key from being flattened out or burred, and the said groove will also operate to prevent the key from being bent or twisted laterally at the lower end. The upper portion of the locking-washer is provided with a pair of lugs 19, having slightly-diverging inner faces, adapted to operate as guides to direct the front edge of the key into the groove should the key and the locking-washer become slightly separated by the closing in of the draft-spring.
- 20 The invention has the following advantages: The draft-rigging is simple and comparatively inexpensive in construction and is adapted to be readily applied to cars and car-couplings without necessitating any material alteration in the construction of the same, and it is especially adapted for vertical-plane car-couplings of the Janney type, as it will prevent a draw-head from falling upon the track and the cars from becoming uncoupled.
- 25 30 should the connection between the draw-head and the draft mechanism become broken. The safety-key, which is arranged to engage the top and bottom of the frame or hanger, is adapted to be readily introduced into the draw-head after the same has been mounted upon a car, and while it may be readily removed when desired it cannot become accidentally displaced.
- Changes in the form, proportion, and the 40 minor details of construction may be resorted to without departing from the principle or sacrificing any of the advantages of this invention.
- 45 50 What I claim is—
1. The combination with a draw-head, of a frame or stirrup receiving the draw-head and composed of vertical sides, a horizontal top provided at its rear edge with an upwardly-extending flange 3^a, and a horizontal bottom extended from the sides to form lateral flanges 6, and a key mounted on the draw-head in

rear of the frame or stirrup and adapted to engage the same, substantially as described.

2. The combination, of a draw-head provided in its shank with opposite slots, and a safety-key consisting of an enlarged body portion fitting within the shank of the draw-head, and arms extending through the slots of the shank and adapted to engage a car, said key being adapted to be partially rotated 60 in the shank of the draw-head to extend its arms through and withdraw them from the said slots, substantially as specified.

3. The combination, of a draw-head provided in its shank with opposite longitudinal 65 slots, and a safety-key consisting of a ball fitting snugly within the shank of the draw-head, and opposite arms extending from the ball and adapted to project through the slots of the shank of the draw-head to engage a 70 car, substantially as described.

4. The combination of a draw-head provided in its shank with slots, a frame or stirrup supporting the same and forming a stop, and a safety-key consisting of an enlarged 75 body portion fitting the opening of the shank, and opposite arms extending through the slots of the shank and arranged to engage the frame or stirrup, substantially as specified.

5. The combination of a draw-head, a tail 80 pin or bolt, a key mounted on the pin or bolt, and a locking-washer provided with a slot to receive the key and adapted to be interposed between the same and a follower-plate, said groove being concave and the edge of the key 85 being rounded to conform to the configuration thereof, substantially as described.

6. The combination of the draw-head, a tail pin or bolt provided with a slot, a key arranged in the slot of the pin or bolt, and a 90 locking-washer provided with a groove to receive the key and designed to be interposed between the same and a follower-plate, said washer being provided with opposite lugs forming a guide, substantially as specified. 95

In testimony that I claim the foregoing as my own I have hereto affixed my signature in the presence of two witnesses.

JOHN CHRISTIE.
